UNITED STATES PATENT OFFICE.

CARL G. LUNDSTROM, OF CLEVELAND, OHIO.

DESIGN FOR A TIRE TREAD.

Application filed December 6, 1922. Serial No. 4,514. Term of patent 3½ years.

To all whom it may concern:

Be it known that I, CARL G. LUNDSTROM, a citizen of the United States of America, residing at Cleveland, in the county of Cuyahoga and State of Ohio, have invented a new, original, and ornamental Design for Tire Treads, of which the following is a specification, reference being had to the accompanying drawing, forming part thereof.

Figure 1 is a plan view of a portion of the tread of a tire showing my new design, and Fig. 2 is a sectional view of the same on the line 2—2 of Fig. 1.

I claim:

The ornamental design for a tire tread, substantially as shown.

CARL G. LUNDSTROM.
